UNITED STATES PATENT OFFICE.

FRIEDRICH MÜLLER, OF VIENNA, AUSTRIA.

INTERNAL-COMBUSTION ENGINE.

Application filed April 3, 1923. Serial No. 629,672.

To all whom it may concern:

Be it known that I, FRIEDRICH MÜLLER, a citizen of the Confederation of Switzerland, residing at IV Prinz Eugenstrasse 80, Vienna, 5 Austria, have invented Improvements in and Relating to Internal-Combustion Engines, of which the following is a specification.

This invention relates to internal combustion engines, in which the injection air 10 compressor is located in the immediate neighborhood of the point of injection and the delivery stroke of the compressor is controlled by the injection valve. The invention is based on the ascertained fact that, 15 owing to the end of the delivery stroke of the compressor coinciding in point of time with the end of the compression period in the working cylinder, in engines of this type no trouble can occur, even if the injection valve should for any reason become leaky. For the injection air produced by the compressor always passes, without loss of volume and with practically undiminished 20 pressure into the working cylinder. According to the invention this fact is made use of for increasing the reliability of the engine for a valveless injection air compressor, in which the compressor suction valve is replaced by suction slits or ports in 25 the wall of the cylinder, which are uncovered by the piston at the end of the outward stroke, while the compression stroke of the compressor is controlled by the injection air valve of the working cylinder. The provision 30 of suction ports does away with the necessity of a check valve for the compressor cylinder, which may cause leakages when the engine is in operation. For the compression stroke in the compressor takes place in 35 a totally enclosed space, as at the commencement of the inward stroke the compressor piston already covers the suction ports, and the injection air cannot escape through valves, which may become leaky after being 40 in operation for some time, as is the case where a compressor suction valve is provided.

Thus the arrangement according to the 45 invention differs from that of engines known hitherto in this, that the compressor cylinder communicates without intermediate members with the atmosphere and through a controlled valve directly with the working cylinder. It has already been proposed to 50 supply air through slits, but only in the case of engines, in which the working cylinder is

placed before the compressor cylinder and the latter is fed with working or scavenging air, which has been previously compressed in the working cylinder. Such arrangements 60 have the disadvantage that, on the admission members for the working air becoming leaky, the compressor will also be affected.

The construction of the compressor cylinder in one piece with the working cylinder 65 or the cylinder head of the engine provides a difficulty, in so far as it is frequently not possible to make the cylinder, which is cast in the interior of a difficult casting, solid and free from pores. According to the invention 70 the compressor cylinder is therefore made in one piece by itself and is inserted in the casting. The cylinder is preferably made so that, besides the suction ports for the admission of atmospheric air, it has a joint 75 making surface in the form of a valve seating, which shuts off the working cylinder, while the injection valve may also be placed in the inserted cylinder.

The accompanying drawing shows a constructional example of the subject of the invention, in which *a* is the working cylinder, *b* the compressor cylinder and *c* the suction ports of the compressor. The compressor cylinder is inserted in the cylinder head of 85 the engine and the injection air is forced at the end of the compression stroke of the compressor, which coincides with the end of the compression stroke in the working cylinder, through the passage *f*, which is controlled by the needle *d* and opens into the injection valve casing *e* and thereupon through the injection nozzle *g* into the combustion space of the engine. The injection valve casing *e* is inserted in the compressor 90 cylinder. The tight joint between the compressor cylinder and the working cylinder can be effected by a ground-in conical surface. The tight joint between the injection valve casing, which is inserted in the compressor cylinder, and the two cylinders can be effected in a similar manner.

With such an arrangement there is no liability to trouble arising, for the compressor has only suction ports in place of the suction valve, which is liable to become leaky owing to wear. No admission valves for compressed air are placed before the suction ports, which communicate directly with the atmospheric air. The admission of the injection air into the compressor takes place 105 at the end of the outward stroke and at the

commencement of the inward stroke of the compressor piston without valves and the compressor cylinder is closed during the compression stroke only by the injection valve of the working cylinder, but even should the injection valve become leaky, no loss of injection air can take place through it, as in the most unfavorable case the injection air will simply enter the working cylinder somewhat sooner, which however will not cause the engine to stop. But even leakages due to the casting being porous are prevented. The compressor is inserted, that is, is made as an independent casting and can therefore be made of specially dense material, which is of great importance, where the pressure of the injection air may go up to 60 atmospheres.

What I claim is:

- 20 1. In combination an internal combustion engine comprising a working cylinder and an injection valve forming the delivery valve of an injection air compressor, a cylinder for the air compressor, a working cylinder head recessed to receive said compressor cylinder, said injection valve extending through the cylinder head and the air compressor cylinder.
- 25 2. In a Diesel engine having individual injection air compressors for each cylinder, a cylinder head, a compressor cylinder in-

serted in a recess in said head and an injection valve casing mounted in recesses in both the cylinder head and the compressor cylinder to control the discharge from said compressor.

3. In combination in an internal combustion engine a working cylinder, a fuel injection valve and a valveless injection air compressor, the delivery valve of which is formed by the injection valve, a cylinder body for said air compressor, the working cylinder having a recess adapted to receive said compressor body, and an injection valve casing adapted to be inserted in a recess in the compressor cylinder body.

4. In an internal combustion engine a working cylinder, an air compressor cylinder body arranged in a recess in the working cylinder at right angles to the axis thereof, and an injection valve arranged in the axis of the working cylinder and passing through a recess in the compressor cylinder body, said injection valve serving as the delivery valve of the air compressor.

In witness whereof I have hereunto signed my name in the presence of two subscribing witnesses.

FRIEDRICH MÜLLER.
